(57) CLAIM

The ornamental design for a sandal cover, as shown and described.

DESCRIPTION

FIG. 1 is a top perspective view of a sandal cover showing my new design;

FIG. 2 is a bottom perspective view of the sandal cover of FIG. 1;

FIG. 3 is a top view of the sandal cover of FIG. 1;

FIG. 4 is a bottom view of the sandal cover of FIG. 1;

FIG. 5 is a right side view of the sandal cover of FIG. 1;

FIG. 6 is a left side view of the sandal cover of FIG. 1;

FIG. 7 is a front side view of the sandal cover of FIG. 1;

FIG. 8 is a rear side view of the sandal cover of FIG. 1;

FIG. 9 is a top perspective view of the sandal cover of FIG. 1 having a sandal therein; and,

FIG. 10 is a bottom view of the sandal cover of FIG. 1 having a sandal therein.

The broken lines in the drawings showing a sandal in FIGS. 9 and 10 depict environment and form no part of the claimed design. The remainder of the broken lines in the figure views depict portions of the sandal cover that form no part of the claimed design.

1 Claim, 4 Drawing Sheets
